UNITED STATES PATENT OFFICE

JOSEPH ESTERMAN AND BARNET GELLMAN, OF LONDON, ENGLAND

FINGER-RING

Application filed July 26, 1929, Serial No. 381,179, and in Great Britain June 7, 1929.

This invention is for improvements in or relating to finger-rings, and is particularly concerned with eternity, posy or hoop rings which have ornamentation or gems or the like 5 around their whole outer surface. With ordinary rings of other types it is comparatively easy to alter the size of the ring by cutting it through and rejoining the ends, but it is not readily possible to do this with 10 eternity and like rings, as the continuity of the ornamentation would be disturbed. It is therefore one of the objects of the present invention to provide means for adjusting the sizes of eternity and like finger-rings.

15 According to the primary feature of the present invention, there is provided a finger-ring comprising an outer rim (for example to receive ornamentation or gems or the like), and one or more annular flanges detachably 20 carried by the ring and intended to bear upon a finger inserted through them. Conveniently, the outer rim provides an undercut seat for the outer edge of each flange so as to retain the flange detachably in position after the manner in which a watch glass 25 is retained in its bezel ring.

There may be only a single flange, if desired, but preferably there will be two such flanges, one at each side of the finger-ring, 30 and of such thickness that when in place in their seats in the outer rim they will lie flush with the sides of the rim. The outer edges of the flanges may be slightly tapered, if desired, in order to facilitate their reception 35 in the undercut seats.

According to another feature of the invention, the outer rim is thickened on its inner face at the middle portion of its width to provide abutments facing the flanges. 40 This thickening will not only serve to strengthen the outer rim, but if the said abutments have faces in the same planes as the inner faces of the undercut seats, the abutments will constitute parts of the seats for the flanges.

Also the said thickening may be discontinuous around the ring so as to provide a pattern effect. For instance, it could take the form of transverse bars located between 50 adjacent gem settings, whereof the ends of

the bars constitute the aforesaid abutments.

For a more complete understanding of the invention there will now be described by way of example only and with reference to the accompanying drawings, certain constructional forms of finger rings according to the invention. It is to be understood, however, that the invention is not restricted to the precise constructional details set forth.

In these drawings,

Figure 1 is a side elevation, on an enlarged scale, of one form of finger-ring according to the invention, parts being removed for the sake of clearness.

Figure 2 is a cross section on the line 2—2 of Figure 1 showing certain parts of the ring detached.

Figure 3 is a detail view looking on a portion of the inside of the ring, and

Figure 4 is a detail cross sectional view of a modified form of ring.

Like reference numerals indicate like parts throughout the drawings.

Referring firstly to Figures 1, 2 and 3, the finger-ring therein shown comprises an outer rim 10 and two annular side flanges 11 and 12. These flanges 11 and 12 are tapered on their outer peripheries 13 and 14 so as to be received in undercut seats 15 and 16 respectively in the rim 10. The flanges are intended to be detachably retained in position in their seats after the fashion in which a watch glass is retained in its bezel ring. The inner peripheries 17 and 18 of the side flanges are intended to bear upon the finger of the wearer and it will be seen that to adjust the finger-ring to suit the wearer, all that is necessary is to fit suitable flanges 11 and 12 to it, the aperture in the flanges being of a size suitable to the finger of the wearer and no alteration to the outer rim 10 being necessary. For one size of outer rim 10 a number of different sizes of flanges 11 and 12 may be available, all of which will fit the seats 15 and 16 in the rim but will have different internal diameters 17 and 18 to suit different sizes of fingers.

The thickness of the flanges 11 and 12 is such that when they are in place in their seats 15 and 16, they will lie flush with the sides of the rim 10. The rim 10 is formed

with perforations 19 so that it may have diamonds or other gems or the like mounted in it and these perforations 19 may be tapered or otherwise suitably formed in order to serve 5 as mounts for the gems.

the middle portion of its width to provide abutments 20, 21, facing the flanges 11 and 12. This thickening serves to strengthen the outer 10 rim and as in the construction illustrated the abutments 20, 21 have their faces in the same planes as the inner faces of the seats 15 and 16, the abutments constitute parts of the seats for the flanges. Moreover, these abutments 15 may be used as guides for the tool in forming the undercut seats. The outer rim with 20 its thickening may be made in one piece of material, or the thickening may be fitted to the outer rim by soldering or otherwise attaching a separately formed ring. The thickening may initially be of the same width as the outer rim, but after having been fixed in position may have its edges cut away so as to leave only the middle portion. In the construction illustrated the perforations 19 for 25 the gems are continued right through the aforesaid thickening, and the latter is made discontinuous around the ring so as to provide a pattern effect. This takes the form of 30 transverse bars 22, located between adjacent perforations 19, the ends of the bars constituting the aforesaid abutments 20 and 21.

The outer faces of the flanges 10 and 11 may 35 be chased or otherwise ornamented in any convenient way as illustrated at 23, Figure 1, and any suitable material may be employed in making up the ring.

In the construction shown in Figure 4, the outer rim 10 is formed integrally with at one 40 side flange 24 and has one detachable flange 25 similar to the flanges 11 and 12 aforesaid. If the internal diameter 26 of the flange 24 is too large for the wearer, alternative 45 detachable flanges 25 could be fitted with smaller internal diameters 27.

It is to be understood that the invention is not restricted to the precise constructional details set forth.

We claim:—

50. 1. A finger ring comprising an outer rim and two exchangeable annular flanges detachably carried by the sides of the rim so as to lie wholly within the width of the rim one towards each side thereof and intended 55 to bear upon a finger inserted through them and constitute the bore of the ring.

2. An eternity or like finger ring comprising an outer rim ornamented continuously around its periphery and formed with an 60 undercut annular seat at its side face, and a detachable annular flange whereof the outer edge is received in the said seat so that its inner diameter shall constitute the bore of the ring, which flange is readily exchangeable with other annular flanges of the same 65

outer but different inner diameter to vary the bore of the ring without changing the diameter of the outer rim.

3. A finger ring comprising an outer rim thickened on its inner face at the middle portion of its width to provide outwardly facing 70 abutments and two annular flanges carried by the rim in contact with the abutments so as to be readily detachable from the rim and abutments and intended to bear upon a finger 75 inserted through them and constitute the bore of the ring, which flanges are readily exchangeable with other annular flanges of the same outer but different inner diameter to vary the bore of the ring without changing the diameter of the outer rim.

4. A finger ring comprising an outer rim formed at its sides with undercut annular seats and thickened on its inner face at the middle portion of its width to provide outwardly facing abutments having faces in the same planes as the inner faces of the undercut annular seats and two annular flanges carried by the rim in contact with the abutments so as to lie wholly within the width of the rim and to be readily detachable from the rim and abutments and intended to bear upon a finger inserted through them and constitute the bore of the ring, which flanges are readily exchangeable with other annular flanges of the same outer but different inner diameter to vary the bore of the ring without changing the diameter of the outer rim.

5. A finger ring comprising an outer rim with a permanent inwardly-directed flange on one side thereof and an annular flange detachably carried on the other side of the rim so as to be readily exchangeable with other annular flanges of the same outer diameter but of different inner diameter equal to or less than the diameter of the bore of the permanent flange, to vary the effective bore of the ring without changing the diameter of the outer rim.

In testimony whereof we have signed our names to this specification.

JOSEPH ESTERMAN.
